UNITED STATES PATENT OFFICE.

CELIA LEVISON, OF CLEVELAND, OHIO.

DESIGN FOR A SPOON.

42,944.

Specification for Design.

Patented Aug. 27, 1912.

Application filed June 29, 1912. Serial No. 706,839. Term of patent 3½ years.

To all whom it may concern:

Be it known that I, CELIA LEVISON, citizen of the United States, residing at Cleveland, in the county of Cuyahoga and State of Ohio, have invented a new, original, and ornamental Design for Spoons, of which the following is a specification, reference being had to the accompanying drawing, forming part thereof.

The figure is a plan view of a spoon, showing my new design.

I claim:

The ornamental design for a spoon, as shown.

CELIA LEVISON.

Witnesses:

JOHN A. BOMMHARDT,
CLARA N. WHITFIELD.
